KNIFE

Dennis P. Bagwell, 206 N. Brockway, Apt. 11,
Palatine, Ill. 60067

Filed May 18, 1973, Ser. No. 361,495

Term of patent 14 years

Int. Cl. D7—03

U.S. Cl. D7—147

fig.1.

fig.2.

fig.3.

fig.4.

fig.5.

fig.6.

FIG. 1 is a side elevational view of a knife showing my new design;

FIG. 2 is a top plan view of the knife shown in FIG. 1;

FIG. 3 is a bottom plan view of the knife shown in FIG. 1;

FIG. 4 is an elevational view of the side opposite that shown in FIG. 1;

FIG. 5 is an end view of the knife shown in FIG. 1 showing the handle end of the knife.

FIG. 6 is an end view of the knife showing the blade end of the knife;

FIG. 7 is an enlarged cross-sectional view taken on line 7—7 of FIG. 1.

I claim:

The ornamental design for a knife, as shown.
